CABLE LASHING DEVICE

Charles J. Weiler, 6839 Oakley St., Philadelphia, Pa.
Filed Sept. 6, 1963, Ser. No. 307,067
5 Claims. (Cl. 254—134.3)

This invention relates to a cable lashing device and its operation in order that a lashed unit may be more uniformly lashed and the lashing operation simpler and better.

It has been customary to helically lash together a plurality of insulated electrical conductors for handling and supporting them as a unit. One use for such a construction has been for the secondary distribution of electric current from an overhead transformer for lighting and for other electric utilization devices. Another use has been in the lashing of telephone conductors to a suspension or messenger wire. Prior processes and apparatus for applying a lashing wire have been too elaborate and not entirely satisfactory. A common practice has been the use of tensioning devices to tightly bind the wire and conductors together as a unit for ease in handling and for improved appearance. However, these tensioning devices have not been uniform in operation for their intended purpose with the result the lashing wire may sometimes be too tight. If the lashing wire is too loose the several conductors are more difficult to handle and unsightly. If the lashing wire is too tight there is danger of the highly stressed lashing wire cutting into the insulation of the conductors and the possibility of a short circuit developing.

A principal object of this invention is to provide a cable lashing device for conductors which is better adapted to bind the conductors together without having the lashing too tight or too loose.

It is a further object of the invention to eliminate the non-uniformity in action of a tension device applied to a lashing wire during helical wrapping around the conductors.

It is a further object of the invention to provide a new and better way of wrapping a lashing wire helically, and then uniformly lightly tensioning the lashing wire after it has been wrapped around the conductors to obtain a snug fit.

It is a further object of the invention to utilize the principle of a slipping friction clutch to preclude more than a desired amount of tension being imparted to the wrapped lashing wire.

It is a further object of the invention to lash a plurality of conductors together in a manner to prevent damage to the conductors and thereby enhance the safety of the conductor.

It is a further object of the invention to provide an improved cable lashing device for conductors utilizing as a component a sleeve of an elastomer to frictionally engage the lashing strand and suitably press it against the conductors.

Other objects and advantageous features of the invention will be apparent from the description and claims.

The nature and characteristic features of the invention will be more readily understood from the following description taken in connection with the accompanying drawings forming part thereof, in which:

FIGURE 1 is a longitudinal view in elevation of the lashing apparatus of the invention;

FIG. 2 is an exploded perspective showing the separate parts of FIG. 1;

FIG. 3 is a longitudinal section on the line 3—3 of FIG. 4;

FIG. 4 is a transverse section on the line 4—4 of FIG. 1.

Referring more particularly to the drawings, as shown in FIGS. 1 and 4, two insulated conductors 10 and 11 are enclosed in a usual form of insulation common in secondary overhead electrical distribution systems. A conductor 13 is shown as being of about the same outside diameter as conductors 10 and 11 with their insulation. In the embodiment shown the conductor 13 may be at ground potential when it is used with energized conductors 10 and 11 and when they have a potential of 240 volts connected across them but for safety have only 120 volts between each of them and the conductor 13. The conductor 13 may be insulated if desired for distribution particularly of three phase current. This conductor is usually aluminum cable steel reinforced for providing the entire support but also may be made of alloys giving it good tensile strength with electrical conductivity.

The cable lashing device shown at L, at the forward or incoming end preferably includes a guide 14 of wood, metal or of a plastic insulator of the type having a smooth surface offering small friction.

The guide 14 has a plurality of openings 15 therethrough, one for each conductor 10, 11 and 13. The leading edges of these guide openings or perforations 15 are preferably round so as not to cut into the insulated surfaces. A holding device, such as a set screw 16, is used to hold the guide 14 in position with respect to a container 17 and with the axis of the three conductors 10, 11 and 13, substantially coincident with the axis of a coil 18 of lashing or lacing material 19. The material 19 can be wire, such as dead soft flexible stainless steel, or a relatively inelastic synthetic plastic in monofilament or strand form.

The support and container 17 for the coil 18 of lashing material 19 is constituted by the inner and outer telescoping portions 20 and 21 shown in FIG. 2. Each such portion 20 and 21 has a tubular projection, the front or incoming projection being designated as 22 and the rear or trailing projection being designated as 23 as shown. The coil 18 of lashing material 19 is supported on its outer surface within the inner portion 20. The outer portion 21 has a sliding fit over the inner portion 20. The telescoping portions 20 and 21 have peripheral flanges 24 and 25, these flanges 24 and 25 being provided with alignable or oppositely disposed holes 26 and 27 through which a tension member such as a wire 28 having twisted ends is passed.

A split rubber line sleeve 30 of a type familiar to electric distribution linemen and of a size to fit snugly over the lashed conductors 10, 11 and 13 is shown in FIGS. 1 and 4. Such a sleeve is shown in the patent to Salisbury, No. 2,927,146, and is of a suitable elastomer, is flexible and is sufficiently stiff to frictionally engage the lashing material and suitably press it against the conductors 10, 11 and 13 as pointed out below. The sleeve 30 has an enlarged end 31 with a greater interior diameter but of lesser length than the remaining portion 32 of the sleeve 30. A taper 33 connects the interiors of the two portions of the sleeve 30, the portion 32 having an inner surface 34.

The sleeve 30 also has a longitudinal slit 35 therealong providing overlapping parts 36 extending slightly more than 90°. The end 31 of the sleeve 30 fits over the rear tubular portion 23 and carries the telescopic container 17 for the lashing material 19. The sleeve 30 has flanges 37 with holes 38 for attachment of flexible tension members 39. The tension support members 39 can be secured at a fixed location, such as a distribution line pole 40. The pull on the tension members 39 tends to pull the sleeve 30 at the flanges 37 into snug gripping relation to the tubular portion 23 thus retaining the line

sleeve 30 in supporting relation to the container 17. The taper 33 assists in keeping or moving the looseness between it and the coil 18, forwardly toward the coil 18 where the looseness in the winding already exists. The inner surface 34 of the longer length and smaller diameter hose portion 32 enables light tension to be placed in the material 19 applied against the conductors 10, 11 and 13, causing the material 19 to hug the conductors 10, 11 and 13, and the tension to be applied can be changed by change in the length of the portion 32. A greater length of the portion 32 gives a greater tension. In other words, the tension of the lashing material 19 and the degree of its pressure on the conductors 10, 11 and 13 can be adjusted by varying the length along which the pressing is effected.

The manner of use will now be pointed out.

With the telescoping portions 20 and 21 of the container 17 assembled with a coil 18 therein and with the guide 14 in place, the inner free end of the lashing material 19 is drawn out through the rear projection 23. The conductor 13 is inserted through one of the openings 15 in the guide 14 and pushed through the assembly including the interior opening in the coil 18, so that it extends about three feet beyond the container 17 where it is attached to the conventional pulling wire (not shown). The other two conductors 10 and 11 are inserted through the other openings 15 in the guide 14, the central opening in the coil 18, and through the rear extension 23, and their ends are taped to the conductor 13 on the length thereof beyond the container 17. The end of the lashing material 19 is taped to the assembled conductors 10, 11 and 13 on the lengths beyond the container 17.

The sleeve 30 is split open along the slit 35, applied around the assembly, permitted to close, and the enlarged end 31 engaged on the projection 23.

The tension members 39 are secured to the pole 40. Upon relative linear movement of the container 17 and the conductors 10, 11 and 13, the lashing material 19 is unwound from the cylindrical inner surface of the coil 18 and helically wound loosely around the conductors 10, 11 and 13.

Movement of the conductors 10, 11 and 13 through coil 18 causes the coil 18 to unwind the material 19 from its inner surface without rotation of either coil 18 or of the conductors 10, 11 and 13 and without a tensioning device being used in the winding. The conductors 10, 11 and 13 are thus wound loosely with the lashing material 19 helically arranged about the conductors 10, 11 and 13, with a pitch dependent upon the existing inside diameter of the coil 18. The inner surface 34 of the sleeve 30 upon the loosely wound lashing has several effects. It presses the lashing material 19 longitudinally and helically, moving the looseness toward the coil 18 where looseness already exists. In doing so the sleeve 30 frictionally exerts enough pressure and tension on the material 19 behind its leading edge to pull the material 19 lightly, and preferably tightly enough to cause the previously applied helical turns of the wire 19 to hug the conductor assembly as shown on FIG. 4. This slight tension is not enough to cause the material 19 to cut into the insulation. This is a safety feature occurring because the action of the inner surface 34 of the rubber sleeve 30 may be likened to the action of a slipping clutch whose slipping precludes more than a desired amount of tension being applied to the lashing material 19 passed over.

The utilization of the sleeve 30 has eliminated the non-uniformity in action which occurred in prior lashing devices. The lashing material 19 is now unwound from the inner surface of the coil 18, passes directly to the conductors 10, 11 and 13 around which the material 19 is wound as comes from this coil inner circumference and is further positioned with the desired tightness by the sleeve 30. The sleeve 30 makes the lashing material 19 conform to or hug the surface of the conductor assembly

in a smooth uniform manner without any danger of the lashing material being snagged by the tensioning apparatus.

The sleeve 30 can be readily removed from the lashed conductor assembly at any time for access to the conductors and is ready for reapplication and reuse without disassembling the container 17.

I claim:

1. In apparatus for winding lashing material about at least partially insulated conductive material, said apparatus including a support for a coil of lashing material, a coil of lashing material in said support, a guide for directing said conductive material through said coil, means for effecting longitudinal relative translation between said conductive material and said coil, said support for said coil passing around the exterior thereof, and an elastomeric elongated sleeve member disposed rearwardly of said coil and fixed with respect thereto and adapted to have passed therethrough in enclosing and snugly contained relationship the conductive material with said lashing material helically applied thereto.

10 2. Apparatus for winding a lashing member about a plurality of strands of at least partially insulated elongated conductive material comprising of coil of elongated lashing member to be wound, a holding device for said coil for delivery of lashing member to said plurality of strands, means for effecting relative longitudinal translation between said strands and said holding device for said coil, and a longitudinally split tubular member relatively longitudinally movable with respect to said strands for snugly pressing said lashing member around said strands upon relative longitudinal movement of said coil holding device and said strands.

20 3. Apparatus for applying an elongated lashing element in helical surrounding relation to a plurality of conductors comprising telescoped tubular members providing a container having a front and rear portion, a conductor guide at said front portion of said container, a coil of lashing element in said container coaxial therewith and surrounding said conductors for delivery of lashing element from the interior of said coil, a longitudinally split sleeve at the rear portion of said container having a central opening receiving said conductors for relative longitudinal movement of said conductors and said lashing element, said sleeve engaging the exterior of said conductors and pressing the lashing element from said coil into engagement with said conductors, and a supporting member for said sleeve.

30 4. Apparatus for snugly fitting a helical lashing material about a plurality of elongated electrical conductors at least one of which is insulated, said apparatus comprising an elastomeric elongated sleeve member, tension means for supporting said member, a coil of lashing material, means supported by said member for containing said coil and maintaining it in axial alignment therewith, means directing said plurality of conductors through said coil and said member for relative translation therewith, said lashing material being unwound interiorly from said coil and about said conductors, and said member frictionally pressing said material toward said conductors upon relative translation between said member and said conductors.

40 5. Apparatus according to claim 4 in which the means for containing said coil comprises telescopic cylindrical members extending around the outside of said coil and at least partially enclosing a trailing end of said coil.
